UNITED STATES PATENT OFFICE

2,444,104

FLEXIBLE DISPENSING SPOUT FOR
CONTAINERS

Rudolph F. Marken, Kansas City, Mo.

Application September 8, 1944, Serial No. 553,172

5 Claims. (Cl. 222—528)

1

This invention relates to containers for pourable substances, and has for a primary aim the provision of a compact, extendible spout, applicable to the container after the same is constructed or adapted to form a part of the body thereof as it is being produced.

This invention has for one of its salient objects, the provision of a dispensing spout for containers that is inexpensive to manufacture, compact when not in use, and which may be extended laterally from one wall on the container to permit the discharge of a given volume of the container's contents without agitating or otherwise disturbing its character.

A further aim of this invention is to provide a dispensing spout for containers, constructable as a unit, applicable to the side of a container without altering the design thereof, and having unique parts disposable to produce a trough-like spout upon manual manipulation of a slidable portion of the spout structure.

Other objects of the invention including the manner of assembling the parts of the dispensing spout; the way in which the sheet material is formed, folded and treated to produce an extensible spout; and the details through the medium whereof the spout is rendered practicable to handle materials, will appear during the course of the following specification, referring to the accompanying drawing wherein:

Fig. 1 is a fragmentary perspective view of a container showing a dispensing spout therefor, attached thereto and made in accordance with the present invention.

Fig. 2 is a similar view but showing the dispensing spout extending to the operative condition.

Fig. 3 is an enlarged fragmentary detailed sectional view taken on line III—III of Fig. 1.

Fig. 4 is a fragmentary vertical sectional detailed view taken on line IV—IV of Fig. 2.

Fig. 5 is a detailed fragmentary cross sectional view taken on line V—V of Fig. 4.

Fig. 6 is a plan view of the back face of the dispensing spout unit removed from association with the container.

Fig. 7 is a fragmentary sectional view through a dispensing spout in an extended condition and embodying a modified form of the invention; and

Fig. 8 is a plan view of a blank forming a part of a dispensing spout, such as that illustrated in Fig. 7.

It has become the current custom to employ containers for liquids, and particularly milk, that are made of fibrous sheet material and which are

2

destroyed after a single use. It is with such a container that the dispensing spout made as illustrated, is particularly useful.

The dispensing spout embodying my invention is, however, applicable to containers of all types from which a pourable substance is to be emptied without opening one of the walls of the container more than to the extent of forming a relatively small window or hole therethrough.

For purpose of clarifying the invention, the preferred embodiment of the dispensing spout as it is associated with a milk container, will be specified.

Container 10 includes at least one side wall 12 against which the pouring spout assembly is secured either during the manufacture of container 10, or after the same has been made, or actually delivered to the customer.

This pouring spout assembly comprises a section of sheet material 14, slit as at 16, 18 and 20 to outline a portion 22 of section 14 that may be swung about hinge-line 24.

When section 14 is in place, its marginal edges are glued, or otherwise secured, as at 26, directly to the outer face of wall 12. This association between section 14 and wall 12 provides a thin pocket 28 wherein lies a flat, flexible element 30 formed in blank, as shown in Fig. 6. Slits 32 extend inwardly from the annular periphery of element 30 to a point on the line of hinge 24, and these slits 32 with the line of hinge lying below element 30, form a tongue 34 which is glued through the employment of adhesive 36, directly to the inner face of section 14.

Element 30 is substantially disc-shaped and a segment thereof on each side of the opening 38, formed when portion 22 is swung outwardly, has a number of embossed lines 40 converging to a point adjacent to the line of hinge 24. That part 40 of element 30 underlying portion 22 is secured thereto by glue or adhesive 42, to the end that when portion 22 is pulled outwardly, the element 30 will follow and establish a trough, such as shown in Fig. 2.

45 This trough is U-shaped in transverse cross section and has parallel upstanding sides formed of the portion of element 30, which is embossed with lines of bend 40. These lines of embossment 40 successively come into engagement with the edges of section 14 formed by slits 16 and 18 as portion 22 is swung outwardly and downwardly to the angle of inclination best suitable for drawing off the liquid within container 10.

A part of element 30 remains between section 55 14 and wall 12 when the pouring spout is formed

and that part remaining is not embossed nor weakened so that it will serve as a limiting element for the outward movement of the embossed portions of element 30. Means is provided, therefore, to stop the movement of parts of element 30 through opening 38.

It is contemplated that this pouring spout assembly shall be placed upon a milk container where the line of hinge 24, and therefore the bottom of the spout, is substantially on or slightly above the cream line of the milk in container 10. After the spout has been formed, a hole 44 is formed through any suitable tool, and after such operation the cream is free to flow from container 10 along the spout and into a suitable receptacle.

The wall of container 10 is provided with perforations or lines of weakness 46 to set off an area in wall 12 substantially in register with opening 38, thus, after the cream has been drawn from container 10, that portion of wall 12 defined by lines 46, may be removed and the milk poured from the container through the spout.

In the form of the invention shown in Fig. 7, an element made of flexible material and having a form such as shown in Fig. 8, is employed. This slightly modified form provides shoulders 48 which are drawn against the inner face of section 14 at the edge formed by slit 20 as illustrated in Fig. 7. Also, the periphery or portion 50 of the edge of this member 52, is eccentric to the line of hinge and therefore, gradually approaches the edge of section 14 formed by slit 20 as shoulders 48 lie near this edge. Shoulder 48 and edge 50, therefore, both establish stops for the limiting of the outward and downward movement of portion 22 and that part of the element 52 which is drawn through opening 38.

In some instances, portion 22 may be eliminated entirely and opening 38 provided through section 14 with the underlying part of either element 30 or 52 extending across opening 38 where it may be grasped and drawn to a condition shown in Fig. 2. In such instances, a lip 54 on element 52 may be gripped by the operator, but where portion 22 is used, a finger-nail notch 56 is cut into portion 22 when slit 20 is created.

The component parts of the pouring spout assembly are preferably made of fibrous sheet material and where the unit is to be applied by the consumer, the same should be packed or otherwise arranged to have the face of element 30 over which the milk is to travel, maintained in a clean and sanitary condition. For example, the unit shown in Fig. 6 may have the face thereof covered by a removable protective sheet that will maintain the exposed surface of element 30 in a clean condition.

The pocket 28 permits the return of the portions of element 30 when the spout has been used whereby hole 44 is closed to preclude the entrance of foreign matter.

It is understood that dispensing spouts for containers having physical characteristics different from those illustrated and described, may be made without departing from the spirit of the invention or scope of the appended claims.

Having thus described the invention, what is claimed as new and desired to be secured by Letters Patent is:

1. A container comprising a closed hollow body formed of sheet material and including a side wall; a section of sheet material secured to the side wall and provided with slits setting off a portion of the said section, said portion being swingable about a line of hinge to an angular

position with respect to the section to leave an opening in the section; and a flat flexible element disposed between the side wall and said section overlying the opening, said element being attached to the set off portion and formed to have a part thereof drawn through the opening from each side thereof when the portion is swung to the angular position to combine therewith in producing a spout, said element having slits therein forming a tongue attached to said section, the portions of said element adjacent each side of the tongue being free to swing laterally therefrom as the said part is drawn through the opening, said portions of the element forming stops to limit the swinging of the said portion and the amounts of the element that are withdrawn through the opening.

2. A container comprising a closed hollow body formed of sheet material and including a side wall; a section of sheet material secured to the side wall and provided with slits setting off a portion of the said section, said portion being swingable about a line of hinge to an angular position with respect to the section to leave an opening in the section; and a flat flexible element disposed between the side wall and said section overlying the opening, said element being attached to the set off portion and formed to have a part thereof drawn through the opening when the portion is swung to the angular position to combine therewith in producing a spout having bottom wall and a pair of spaced-apart side walls extending from the bottom wall, said flat flexible element having a pair of segments having arcuate edges, each edge being provided with a shoulder extending radially outwardly therefrom to engage the section when the set off portion has reached a predetermined angular position extending outwardly and downwardly from the section, said segments each merging with a respective side wall of the element forming said spout.

3. A container comprising a closed hollow body formed of sheet material and including a side wall; a section of sheet material secured to the side wall and provided with slits setting off a portion of the said section, said portion being swingable about a line of hinge to an angular position with respect to the section to leave an opening in the section; and a flat flexible element having a fixed and a shiftable part disposed between the side wall and said section attached to the set off portion and formed to have a segment of the shiftable part thereof drawn through the opening when the portion is swung to the angular position to combine therewith in producing a spout, other segments of the shiftable part being formed to remain between the side wall and the section when the spout is produced, to limit the swinging movement of said portion, the part of the element drawn through the opening being substantially U-shaped in transverse cross section.

4. A container comprising a closed hollow body formed of sheet material and including a side wall; a section of sheet material having its marginal edges secured to the side wall to form a narrow pocket and having an opening provided therethrough; and a flat flexible element disposed in the pocket formed to have a part thereof rendered sufficiently flexible to be drawn through the opening and into angular position to the side wall to produce a spout, said flat flexible element having relatively inflexible portions incapable of being drawn through the opening and

forming stops thereon to limit the amount of the element drawn through the opening, said portions being movable laterally away from each other as the element is drawn through the opening.

5. A container comprising a closed hollow body formed of sheet material and including a side wall; a section of sheet material secured to the side wall to form a pocket and provided with slits setting off a portion of said section, said portion being swingable about a line of hinge to an angular position with respect to the section to leave an opening in the section; and a normally flat flexible element of sheet material disposed in the pocket, said element being slit to define a part having attachment to the said section to prevent relative bodily movement of the element with respect to the side wall and the section, and a part having attachment to the set off portion of the section provided with areas drawable through the opening from each side respectively thereof when said portion is swung to

the angular position to combine therewith a pair of side walls and a bottom wall, and areas remaining in the pocket to serve as stops when the first mentioned areas are extended, that part of the element forming the side walls of the spout being movable from a position substantially parallel to the section to a position perpendicular thereto as the same is moved from and to the spout forming position respectively.
